UNITED STATES PATENT OFFICE.

JOSEPH JAMES DUCKWORTH, OF SALT LAKE CITY, UTAH, ASSIGNOR OF FIFTY-TWO PER CENT TO T. O. DUCKWORTH, OF SALT LAKE CITY, UTAH.

LIFTING DEVICE.

Original application filed February 2, 1924, Serial No. 690,254. Divided and this application filed August 5, 1926. Serial No. 127,395.

This invention relates to pumps for lifting liquids and is directed particularly to an improved valve cage and the details thereof whereby it may cooperate with a special device for lifting the cage through the pump cylinder.

One feature is the construction of the removable cage which has a central opening at the top through which a valve ball may be inserted. After the ball is inserted, radially extending lugs are screwed centrally into the top opening, thus serving the dual function of preventing the upward displacement of the ball and also constituting means by which the cage may be lifted with the use of a peculiarly shaped grapple device which is described and claimed in my copending application Serial No. 690,254, now Patent No. 1,600,956, from which this application has been divided.

The above and additional features and advantages will be described and claimed in detail in the following specification and claims, and illustrated in the accompanying drawings, in which:

Figure 1 is a central vertical sectional view showing a pump cylinder having the particular valve cage of the present invention located at its lower end;

Figure 2 is a view of the same pump cylinder as illustrated in Figure 1 with the lower valve cage shown in elevated position as lifted by the particular grapple device shown in Figure 5;

Figure 3 is a view looking downwardly at the top of the valve cage when the grapple device of Figure 5 is being introduced into the top of the valve cage;

Figure 4 is a sectional view taken on the line 4-4 of Figure 2, looking downwardly and illustrating how the grapple radially projecting arms engage and support the corresponding lugs of the valve cage; and

Figure 5 is a front elevation of the grapple device used for engagement with the lugs of the valve cage.

Like reference characters refer to like parts of the different figures of the drawings.

Referring in detail to the drawings, the figures illustrate a pump cylinder having in conjunction therewith a lower cage valve with a ball therein and a working plunger likewise provided with a ball valve. 1 is the

cylindrical cylinder of a pump in which a 55 plunger 2 is mounted on the lower end of a pump rod 3 (see Fig. 1). The working plunger 2 has a close fit with the cylinder walls and has its upper end 2^a provided with a central threaded opening 2^b for the reception of a pump rod and also a plurality of openings 2^c through which liquids to be lifted may pass upwardly during the working movement of the plunger. The extreme upper end wall of the plunger is terminated 65 with a relatively sharp edge adjacent the cylinder wall which is so designed in order that sand or like abrasive material will not tend to collect adjacent the cylinder wall and injure the same. A recess 2^d is provided 70 at one side of the upper end of the plunger, through which a cotter pin 3^a extends to lock the pump rod 3 with respect to the plunger 2. The lower end of the plunger 2 is provided with an internal threaded portion 2^e in which a flanged collar 4 projects, a threaded extension 4^a of the collar engaging the threaded portion 2^e of the plunger. A locking set screw 6 projects from the lower face of the flange 4 upwardly and engages 75 the threaded portion 4^a and the plunger wall to lock these parts against relative rotation. A ball 5 is normally positioned within the central hollow space of the plunger and during the lifting movement of the 80 plunger the ball normally rests on the upper inner circular edge of the portion 4^a, thus closing the opening through the flanged collar 4 and preventing passage of liquid downwardly through the plunger. To remove the 85 ball from within the plunger or to insert it in the plunger, it is necessary to remove the locking screw 6 and to unscrew the flanged collar 4 from the plunger 2.

The cage valve 7 is positioned at the lower 95 end of the pump cylinder 1 and projects below the pump cylinder. The cage valve 7 has a main body portion with a cylindrical exterior and which is removable upwardly through the length of the pump cylinder, 100 as will be described. 7^a is a beveled seat within the body of the cage upon which seat the ball 8 is adapted to normally rest. At the extreme lower end of the valve cage there are a plurality of openings 7^b through 105 which liquid enters during the lifting stroke of the pump. At the upper end of the cage there is an annular laterally projecting

flange 7^c, the outside diameter of which is slightly less than the inside diameter of the pump cylinder. The cage 7 has upper end openings with side walls 7^d. The cage is supported at the extreme lower end of the cylinder 1 by means of a screw-threaded collar 9 which has an inwardly extending flange 9^a loosely encircling the cylindrical body of the cage 7 and on the upper surface of which the lower side of the flange 7^c of the cage is adapted to rest and provide a comparatively water-tight fit. The lower end of the pump cylinder 1 is screw threaded at 1^a to receive the collar 9.

15 The lifting device for removing the valve cage 7 upwardly through the pump cylinder will now be described. In the upper portion of the valve cage 7 are a plurality of lugs 10 which extend radially and centrally from the side wall 7^d and thus project into the upper end opening of the cage. These lugs are illustrated in Figures 1 and 2 as screw threaded through the wall of the cage and through the projecting flange 7^c. As 20 shown in Figures 3 and 4, the lugs 10 project only sufficiently far so that they may be engaged by a grapple device which is insertable centrally through the upper end opening of the valve cage, as will be described. The grapple device shown in side elevation in Figure 5 consists of a body block member 11 having a central opening 10^a, (see Figure 2) for the reception of the threaded end of an operating rod. A plurality of radially extending arms 11^b are shown as having grooves or notches in their upper surfaces in which the lugs 10 are adapted to be seated when the grapple device is brought into engagement with the 25 valve cage and with the lugs for the removal of the cage upwardly. Preferably, the upper portion of the block 11 is tapered, as shown in Figs. 2 and 5, so that it may be guided easily into position during the upward movement.

When the cage is in position at the lower end of the pump cylinder, as illustrated in Figure 1, and it is desired to lift the cage upwardly, the following general procedure 30 is followed. The pump rod 3 and the plunger 2 are drawn upwardly and removed from the cylinder. The pump rod 3 may then be disconnected from the plunger or a similar rod may be used and the rod or its substitute is threaded into the opening 11^a of the 35 grapple device 11. The device is then lowered downwardly and inserted into the upper end opening of the valve cage 7, and downwardly along the wall 7^d, substantially as represented in Figure 3, the arms 11^b lying between adjacent lugs 10. Then the 40 rod 3 and the grapple device 11 is rotated with respect to the valve cage until the arms 11^b are brought into registry immediately beneath the lugs 10. The device is then

lifted upwardly and the lugs become seated in the grooves of the arms 11^b, and the valve cage may then be drawn upwardly through the pump cylinder, substantially as shown in Figure 2.

It will thus be understood that the present invention provides an improvement in lifting pumps whereby the lowermost or foot valve may be removed without necessitating the removal of the entire pump cylinder or other pipe on which the valve is mounted. The invention includes also the peculiar position of the valve cage which is located chiefly below the cylinder and yet may be removed upwardly through it.

The material of which the parts are constructed may satisfactorily include a steel tube or cylinder, a brass or bronze plunger working within the cylinder, and a lower foot valve cage which likewise is preferably of brass or bronze. The valves include balls which may be of solid rubber or other relatively heavy durable material which will serve to close the respective openings in the plunger and the foot valve.

I claim:—

1. In pump apparatus having a pump cylinder and a pump part removable upwardly through the cylinder, the combination with a plurality of centrally extending lugs carried on said pump part and having their adjacent ends spaced from each other, of a lug engaging element adapted to enter endwise between the spaced ends and adapted to be rotated with respect to said ends and to engage the under faces of said lugs whereby said pump part is removable upwardly, said lug engaging element including a body block and means for coacting with said lugs, said body block having its upper portion tapered toward the upper end whereby from a location below the lugs the block may be guided upwardly into position between the spaced ends of said lugs.

2. In pump apparatus having a pump cylinder and a pump part removable upwardly through the cylinder, the combination with a centrally extending lug carried on said pump part, of a lug engaging element adapted to be moved endwise of said cylinder and said pump part until it is below the level of said lug, then rotated with respect to said pump part until said lug engaging element registers with and engages said lug and then moved upwardly to raise said pump part, said lug and said lug engaging element having a complementary projection and seat for receiving said projection whereby accidental angular displacement of said projection and seat is prevented.

3. A device for lifting pump parts from pump casings and cylinders from the said device comprising a body block adapted to be lowered centrally down a pump cylinder,

radially extending arms carried by said body block and adapted to engage their upper surfaces with the under surface of a corresponding part of a pump part to be lifted, said arms having on their upper side an irregular surface adapted to engage a complementary surface on the under face of the pump part to be engaged by said arms, whereby the irregularity prevents accidental angular slip between the parts.

4. A device for lifting pump parts from pump casings and cylinders from the said device comprising a body block adapted to be lowered centrally down a pump cylinder, radial arms carried by said body block and extending toward the wall of said pump cylinder, said arms having grooves on their

upper surfaces in which grooves corresponding parts of a pump part are adapted to seat when the part is lifted.

5. A device for lifting pump parts from pump casings and cylinders from the said device comprising a body block adapted to be lowered centrally down a pump cylinder, radial arms carried by said body block and extending toward the wall of said pump cylinder, said arms having grooves on their upper surfaces extending to the ends of the arms in which grooves corresponding parts of a pump part are adapted to seat when the part is lifted.

In testimony whereof I affix my signature.

JOSEPH JAMES DUCKWORTH.
